W. KENNEDY

SWIMMING WING

Original Filed Nov. 22, 1923

William Kennedy,
George Heidman
Attorneys

UNITED STATES PATENT OFFICE.

WILLIAM KENNEDY, OF CHICAGO, ILLINOIS, ASSIGNOR, BY DIRECT AND MESNE ASSIGNMENTS, TO AIRUBBER CORPORATION, OF CHICAGO, ILLINOIS, A CORPORATION OF ILLINOIS.

SWIMMING WING.

Application filed November 22, 1923, Serial No. 676,215. Renewed September 7, 1926.

- My invention relates to a device to be employed by swimmers or bathers; the invention contemplating a device in the nature of swimming wings of such construction as to 5 accommodate itself readily to the body of the user and which may be easily applied in a manner which will not interfere with the free movement of the user nor with the ability of the swimmer.
- 10 One object of my invention is to provide a device wherein the opposite ends or wings are separately inflatable; the inflatable portions or wings being connected together by a non-inflatable band or strap which is 15 adapted to fit across the chest or body of the user with the inflatable portions or wings disposed rearward of the arms and adjacent to the shoulders of the user so as to maintain the user afloat; the connecting band or 20 strap having any suitable shape, preferably of narrow width and preferably composed of non-elastic material.
- Another object of my invention is to provide a swimming device which is air tight; 25 economical in construction; comparatively cheap to manufacture and provided with suitable valves of simple and efficient construction whereby accidental deflation of the inflated portions or wings will be prevented.
- 30 The above enumerated objects and the advantages inherent in my invention will all be more readily comprehended from the detailed description of the accompanying drawing, wherein:—
- 35 Figure 1 is a plan view of my improved swimming wing.
- Figure 2 is an enlarged detailed sectional view taken on the line 2—2 of Figure 1 looking in the direction of the arrows; showing 40 the portion or wing partially inflated.
- Figure 3 is an enlarged detail view taken on the line 3—3 of Figure 1.
- Figure 4 is a detail sectional view showing a modification of the invention.
- 45 The purpose of my invention is to provide a swimming device which may be readily applied to the body of the bather or swimmer without employing fastening means and wherein the inflatable or air-holding portions or wings will readily and properly 50 position themselves when the user enters the water. In order that the inflatable portions will in no way interfere with the free movement or action of the bather or swimmer, it is preferable that the inflatable portions or 55 wings be of less width or dimensions at the points where they are connected to the connecting strap or band, namely at a point adjacent to the body and arms of the user. For this reason, the inflatable portions or 60 air-holding bags 10, 10 are preferably shown somewhat pear-shape or oblong, with the reduced ends 11, 11 provided with a band or strap 12 preferably of non-elastic material and of comparatively narrow width as 65 shown in Figure 1. The band 12 is of any suitable fabric, with the ends thereof preferably folded upon themselves, as shown at 70 13 in Figure 3, so as to reenforce the ends where they are suitably stitched or otherwise securely fastened to the marginal portions 14 at the reduced ends 11 of the inflatable portions or wings 10.
- In the construction shown in Figures 1 and 2, my improved swimming wing has the 75 air-holding portions or inflatable wings formed of a suitable rubberized fabric composed of a pair of similarly shaped or cut sheets 15 and 16 having the marginal edges thereof vulcanized together as at 17 in 80 Figure 2; while the reduced portion or neck 11 is vulcanized at the point indicated at 18 so as to leave the unvulcanized end or marginal portion 14 to which the band or strap 12 is preferably stitched as shown in order 85 that the stitching will in no way interfere with or in any way affect the air-holding wings or portions.
- The reduced portions 11 of both wings 10, 10 at points adjacent to the stitching 14, are 90 each provided with a short rubber tubing 19, preferably arranged so as to be disposed upwardly and in a slightly inclining manner as shown in Figure 1 so as to be in easy reach of the mouth of the user. The inner 95 end of the tube 19 is provided with a suitable ferrule 20, see Figure 3, arranged within the tube to reenforce the latter and permit the fabric constituting the wings to be vulcanized about and onto the rubber tubing at 100 the point indicated at 21 in Figure 3 and thus provide an absolute air tight connection or seam.
- Each tubing is provided with a valve member in the nature of a plug or pin 22, 105 preferably provided with a rounded or blunt end and with a head portion 23 of dimensions slightly larger than the diameter of the

tube; the plug proper being of a size slightly greater than the internal diameter of the tube 19 for the purpose of providing a secure and snug fit. This simple valve construction not only permits the easy opening and closing of the tubing, but also provides a valve which cannot easily be affected or shifted to allow escape of air.

With the separately inflatable portions or wings having no air transmitting connection therebetween, it is evident that injury or puncture of one of the portions or wings will in no way affect the other, with the result that the entire buoyant effectiveness or capacity of the swimming wing is not destroyed under such conditions.

In Figure 4, I show a modification of the invention, wherein the wing portions or bags 24 are composed of any suitable fabric and each wing or portion 24 provided with a small inflatable elastic rubber bag 25, preferably of pure rubber, and normally of materially smaller dimensions than the outer bags 24, and also preferably of oblong or pear-shape similar to the outer bags 24. Each inner bag 25 is provided with a small rubber tube 26, either integrally connected therewith or otherwise suitably secured thereto, as for example by means of a thread or band wound about the neck of the bag 25 and the end of the tube 26 as shown at 27; in which event the inner end of the tube 26 is also preferably provided with a ferrule like that shown at 20 in Figure 3. The tubes 26 extend through suitable eyeleted openings as shown at 28, in snug fitting relation therewith so as to maintain the rubber bag 25 in place when the latter is deflated, especially when the rubber bags 25 are normally smaller than the outer portions or bags 24; the eyeleted openings 28 in the respective portions or wings being so arranged that the tubes 26 will be disposed upwardly at an inclination as shown in Figure 1 so as to be within easy reach of the mouth of the user. These tubes, like tubes 19, are provided with the closures or plugs 22 as shown in Figure 3, of such size as to slightly distend the ends of the tube and provide a firm sealing relation therewith to prevent accidental withdrawal and also prevent the escape of air. The fabric portions or wings 24 are suitably secured to the non-elastic and non-inflatable strip or band 12, preferably by hemming or suitably sewing the bags or portions 24 and ends of the band together as shown.

The wings or bags are preferably of the

oblong or more or less pear-shape because this permits the device to adapt itself readily to the body of the user; although different shapes may be employed and the wings provided with a reduced or neck portion at a point where the wings or bags are secured to the non-elastic band or strap 12. My invention provides a swimming wing or device which is economical and inexpensive in manufacture, because the various portions of the swimming wings may be cut into shape without expensive waste of material, while at the same time providing a device which will remain inflated and wherein the inflatable portions or wings are independent of each other and of sufficient capacity to maintain the swimmer afloat in the event of one of the wings or portions becoming inoperative or punctured.

The constructions shown I believe to be the simplest and best adaptations of the invention, which have been described in terms employed merely as terms of description and not as terms of limitation, as modifications are possible and may be made without, however, departing from the spirit of my invention.

What I claim is:—

1. A swimming wing composed of a pair of separately inflatable air-holding bags having an outer surface of fabric and formed with a reduced portion or neck provided with a tube-receiving opening, an air-introducing tube disposed through said opening and having a reinforcing ferrule within the inner end thereof, a plug member insertable in the outer end of each tube, and a non-elastic strap or band secured at its ends to the air-holding bags.

2. A swimming wing composed of fabric formed to provide a pair of independent wing portions or bags, each provided with a reduced end, the upper side of the reduced end of each bag being provided with an opening, an inflatable elastic bag, of normally smaller dimensions, having a reduced end, arranged in each of said first mentioned bags or wing portions, the reduced ends of the elastic bags being each provided with a tube disposed upwardly through the opening in the outer bag and in snug fitting relation therewith so as to prevent shifting of the elastic bag, closures for each of said tubes, and a non-elastic and non-inflatable flexible band secured at its ends to the reduced ends of the first mentioned bags or wing portions.

WILLIAM KENNEDY.
